(57) **CLAIM**

The ornamental design for a small fold down wall mount laptop desk, as shown and described.

DESCRIPTION

FIG. 1 is a perspective view of a wall mount desk showing my new design in a configuration with the working surface and drawer in closed positions.

FIG. 2 is a frontal view thereof.

FIG. 3 is a rear view thereof.

FIG. 4 is a top view thereof.

FIG. 5 is a bottom view thereof.

FIG. 6 is a left side view thereof.

FIG. 7 is a right side view thereof.

FIG. 8 is a perspective view of the wall mount desk showing my new design in a configuration with the working surface in a closed position and the drawer in a partially open or extended position.

FIG. 9 is a frontal view of the wall mount desk depicted in FIG. 8.

FIG. 10 is a top view of the wall mount desk depicted in FIG. 8

FIG. 11 is a bottom view of the wall mount desk depicted in FIG. 8

FIG. 12 is a left side view of the wall mount desk depicted in FIG. 8

FIG. 13 is a right side view of the wall mount desk depicted in FIG. 8

FIG. 14 is a perspective view of the wall mount desk showing my new design in a configuration with the working surface in an open or extended position and the drawer in a closed position.

FIG. 15 is a frontal view of the wall mount desk depicted in FIG. 14.

FIG. 16 is a top view of the wall mount desk depicted in FIG. 14.

FIG. 17 is a bottom view of the wall mount desk depicted in FIG. 14.

FIG. 18 is a left side view of the wall mount desk depicted in FIG. 14; and,

FIG. 19 is a right side view of the wall mount desk depicted in FIG. 14.
